UNITED STATES PATENT OFFICE.

NATHAN REISMAN, OF CLEVELAND, OHIO, ASSIGNOR TO H. BLACK AND COMPANY, OF CLEVELAND, OHIO, A PARTNERSHIP.

DESIGN FOR A WOMAN'S COAT.

No. 39,044.

Specification for Design.

Patented Jan. 28, 1908.

Application filed November 18, 1907. Serial No. 402,767. Term of patent 3½ years.

To all whom it may concern:

Be it known that I, NATHAN REISMAN, a citizen of the United States, residing in Cleveland, in the county of Cuyahoga and State of Ohio, have invented a new, useful, and ornamental Design in Women's Coats, of which the following is a specification, reference being had to the accompanying drawing, forming a part thereof.

I claim:

The ornamental design for a woman's coat as shown.

NATHAN REISMAN.
